(57) CLAIM

The ornamental design for a burnable insect-repellant coil, as shown and described.

DESCRIPTION

FIG. 1 is a front perspective view from above of a burnable insect-repellant coil showing the new design; FIG. 2 is a top plan view, the bottom plan view being the reverse thereof;

FIG. 3 is a front elevational view, the rear elevational view being identical thereto; and,

FIG. 4 is a left-side elevational view, the right-side elevational view being identical thereto.
